UNITED STATES PATENT OFFICE.

MAURICE BLUMENTHAL, OF BROOKLYN, NEW YORK.

TOOL FOR DETACHING OBSTRUCTIONS FROM ELECTRIC-WIRE CONDUITS.

1,160,829.

Specification of Letters Patent.

Patented Nov. 16, 1915.

Application filed March 10, 1915. Serial No. 13,494.

To all whom it may concern:

Be it known that I, MAURICE BLUMENTHAL, a citizen of the United States, and residing at Brooklyn, in the county of Kings 5 and State of New York, have invented certain new and useful Improvements in Tools for Detaching Obstructions from Electric-Wire Conduits, of which the following is a specification, such as will enable those skilled 10 in the art to which it appertains to make and use the same.

This invention relates to tools or implements for detaching obstructions from the interior of electric wire conduits used for 15 telegraph, telephone and other purposes, and which are usually employed in connection with what are known as "jar rods" which are usually composed of detachably connected parts so that the length thereof 20 may be increased or decreased, as desired, said rods being adapted to be detachably connected with the tool or implement; and the object of the invention is to provide an improved tool or implement of this class 25 which is effective in operation and which may be used either in conduits which are tubular or conduits which are rectangular in cross section and in either what are called single or multiple conduits; and with this 30 and other objects in view the invention consists in a device of the class specified, constructed as hereinafter described and claimed.

The invention is fully disclosed in the 35 following specification, of which the accompanying drawing forms a part, in which the separate parts of my improvement are designated by suitable reference characters in each of the views, and in which:

40 Figure 1 is a sectional side view of one form of my improved tool or implement; Fig. 2 a view similar to Fig. 1 but showing a modification; Fig. 3 a cross section on the line 3—3 of Fig. 1; Fig. 4 a view similar 45 to Fig. 1 but showing another form of my improvement; and, Fig. 5 a cross section on the line 5—5 of Fig. 4.

In the practice of my invention, reference 50 being made to Figs. 1 and 3, I provide a tool of the class specified which is tubular in form and circular in cross section, and which comprises a body portion α open at one end and closed at the other, and the closed end α^2 is preferably tapered as shown 55 at α^3 and provided with a shank α^4 which is rectangular in cross section and preferably

square, and the outer end of the shank α^4 is provided with a cylindrical head α^5 by means of which the tool may be connected with a "jar rod" as in other devices of this class. 60

The open end of the tool is provided with projecting teeth α^6 which are preferably curved outwardly, and the closed end portion of the tool is provided, in the form of construction shown, with a transverse partition α^7 having a central perforation α^8 , and the partition α^7 forms in the closed end of the tool a chamber α^9 , and in the top wall of said chamber is an aperture α^{10} adapted to be closed by a screw plug α^{11} or any other 70 suitable means.

In the laying of conduits of the class specified it is customary to abut the separate sections of the conduit and to inclose the abutting ends of said sections with concrete 75 or similar material, and this concrete while in a plaster state works into the conduit between the abutting ends of said sections and forms, when set or hard, obstructions which prevent the passage of wires or cables 80 through the conduit, and it is these obstructions that my improved tool or implement is designed to remove and by making the said tool or implement hollow or tubular in form, the obstructions when detached may 85 to a large extent be collected in the tool, in the operation thereof, and withdrawn from the conduit with the tool, and in the use of this device the chamber α^9 is filled with water, or partially filled, and this water 90 passes slowly through the aperture α^8 in the partition α^7 in the use of the tool and facilitates the detachment of the obstructions.

In Fig. 2 I have shown a modification of 95 the construction shown in Fig. 1 in which the open end of the body of the tool is provided with tubular sleeves b secured therein in any way, and which are provided at their outer ends with teeth b^2 similar to the teeth 100 α^6 , and the teeth of the inner sleeve alternate with those of the outer sleeve which in turn alternate with the teeth α^6 of the body of the tool. The operation of this form of tool will be the same as that shown in Fig. 1 but the 105 sleeves b form a supplemental chamber b^3 in the body of the tool which, in the operation thereof, receives the detached obstructions or a portion thereof, and said obstructions are removed with the tool from the conduit. 110

In Figs. 4 and 5, the body c of the tool is rectangular in form and preferably square,

and with this exception the construction is the same as that shown in Fig. 1, and this form of the tool may also be provided with the sleeves *b*, if desired, and the operation of this form of construction will be the same as the operation of the form shown in Figs. 1 to 3 inclusive.

Having fully described my invention, what I claim as new and desire to secure by 10 Letters Patent, is:-

1. A tool for use in cleaning out electric cable conduits, said tool comprising an oblong hollow body portion, the side walls of which are entirely closed, and said tool being open at one end and closed at the other, and the open end being provided with peripheral projecting teeth.
2. A conduit cleaning tool of the class described, said tool comprising an oblong hollow body portion, the walls of which are parallel, the side walls of said body portion being entirely closed, and said tool being open at one end and closed at the other, and the open end being provided with peripheral projecting teeth, and said body portion being also provided adjacent to the closed end with a transverse partition having a small aperture and forming a water chamber one side wall of which is provided with an orifice through which said chamber may be filled, and means for closing said orifice.
3. A conduit cleaning tool of the class de-

scribed, comprising an oblong box-shaped body portion open at one end and closed at the other, the closed end being provided with means for attaching a "jar rod" thereto and the open end being provided with supplemental inner sleeves which are secured therein, and said open end of the body portion and said sleeves being provided with 40 projecting teeth.

4. A conduit cleaning tool of the class described, comprising an oblong box-shaped body portion open at one end and closed at the other, the closed end being provided with means for attaching a "jar rod" thereto and the open end being provided with supplemental inner sleeves which are secured therein, and said open end of the body portion and said sleeve being provided with 45 projecting teeth, and said body portion being provided adjacent to the closed end thereof with a transverse partition forming in said end a water chamber and having a small aperture.

In testimony that I claim the foregoing as my invention I have signed my name in presence of the subscribing witnesses this 8th day of March 1915.

MAURICE BLUMENTHAL.
